United States Patent

Des. 238,344

Patented Jan. 6, 1976

238,344

SONIC SIGNAL GENERATOR

David L. Livermore, Seattle, Wash., assignor to Proctor & Associates Company, Redmond, Wash.

Filed Dec. 12, 1973, Ser. No. 424,163

Term of patent 14 years

Int. Cl. D10—06

U.S. Cl. D10—116

FIG. 1 is a perspective view of a sonic signal generator showing my new design;

FIG. 2 is a front elevational view;

FIG. 3 is a left side elevational view;

FIG. 4 is a top plan view;

FIG. 5 is a rear elevational view;

FIG. 6 is a right side elevational view; and

FIG. 7 is a bottom plan view.

I claim:

The ornamental design for a sonic signal generator, as shown.
